UNITED STATES PATENT OFFICE

CLARENCE M. HOLLEY, OF HIGHLAND PARK, AND HOWARD L. FOSTER, OF DETROIT,
MICHIGAN; SAID HOLLEY ASSIGNOR TO SAID FOSTER

ARTIFICIAL REFRIGERATING APPARATUS

Application filed September 15, 1922. Serial No. 588,325.

This invention relates to artificial refrigerating apparatus, and the object thereof is to provide a simple and compact refrigerating apparatus that is attachable as a complete unit to a refrigerating box or storage compartment. A further object is to provide a compact structure that may be attached to or removed from the refrigerator, as a unit, without detaching any of the component parts of the unit or disconnecting any of the elements one from the other. A further object of the invention is to provide a unit of the character stated, carried in a casing that may be attached to a refrigerator box, projecting thereinto, with the cooling coils or element on the outside of the casing, and the apparatus for producing the cold, within the casing or compartment, that is shielded from the storage compartment and into which atmospheric air may be drawn and discharged for the cooling of the compression coils of the system, as is hereinafter more fully described.

As is well known, there are two structures commonly in use in artificial refrigeration, in one of which the expansion coils are in direct contact with the air to be cooled and in the other of which the expansion coils are immersed in a brine which provides the cooling element. It is not material to this invention which type of refrigerating apparatus be utilized, the invention in this instance residing in the unit adapted to be attached to the refrigerator box, comprising a compartment for containing the operative mechanism, exteriorly of which is provided the cooling element (either the brine type or direct type as mentioned), the compartment containing the apparatus being heat insulated from the refrigerator compartment and being open to atmosphere. Another feature of the invention resides in the arrangement of the operative parts whereby compactness is secured, and the said parts being subjected to a flow of air thereby tending to prevent overheating of the same.

The principal feature of the invention briefly is to provide a small and compact unit that is adapted to be placed in any of the usual types of refrigerator box in use by

the householder. At the present time most households are provided with a refrigerator utilizing natural ice as the cooling medium and many types of artificial cooling apparatus at present in use are built into a box especially designed for the apparatus requiring that the householder discard or dispose of his ice box in order to avail himself of the usual type of artificial refrigerating apparatus. This is expensive and we have therefore devised artificial cooling apparatus of such compact form that it may be introduced into the usual ice compartment of the ordinary ice box thus making artificial refrigerating apparatus available for persons of moderate means. Another feature of the invention is in so constructing the unit that the door of the ice compartment may be removed and this apparatus introduced, the apparatus being provided with a frame that may be cut at the periphery and shaped to fit the door opening and may be permanently attached thereto if desired but preferably removable to permit a change of units when repair is required. By this arrangement the cost of the refrigerator box is avoided, the householder being enabled to utilize the structure that is already installed. These and other objects and novel features of the invention are hereinafter more fully described and claimed, and the preferred form of construction of refrigerating apparatus embodying our invention is shown in the accompanying drawings in which—

Fig. 1 is a vertical section showing our improved unit as applied to an ordinary refrigerator box and indicating one type of artificial refrigerating apparatus.

Fig. 2 is a similar view showing the unit of the brine tank type in the same general relationship as with the apparatus shown in Fig. 1.

Fig. 3 is a front elevation showing the ice chamber with one type of frame utilized with our improved unit.

Fig. 4 is a cross section thereof taken on lines 4—4 of Fig. 3.

Fig. 5 is a front elevation of part of a refrigerator box showing our improved unit in place.

In the usual type of artificial refrigerating apparatus utilizing sulphur dioxide or similar refrigerant, there is employed a pump or compressor indicated at 1 in Fig. 1 which compresses the refrigerant transferring the same to the high pressure coils 2 from which it passes by means of line 24 to an expansion valve 3 and thence to the expansion or low pressure coils 4 returning to the pump by means of the line 5. To secure compactness we have arranged an electric motor 6 having a shaft 7 extending forwardly of the motor to the fan 8 and rearwardly thereof into the pump case and, as will be understood, operatively connected with the crank shaft or other means utilized to operate the compressor, the compressor preferably being of the air cooled type for which reason fins 9 are provided on the compression end of the pump cylinder. This mechanism is housed within the chamber indicated generally at 10, this chamber being formed by the heat insulated walls 11 extending entirely thereabout on five sides, the sixth or front side being open to the front of the refrigerator and occupied by the high pressure coils 2 through which the fan 8 draws air into the compartment to cool and condense the fluid in the high pressure lines 2. We also provide a deflector plate 12, one end of which is secured to the top of the motor and the other end of which extends upwardly therefrom to the coils 2 near the top. This plate extends entirely across the chamber 10 from side to side and air drawn through the coils 2 by the fan is blown backward into the chamber 10 about the compressor and motor and thence outward above the deflector to atmosphere through the channel 13. Preferably a frame indicated at 14, is placed over the coils 2 having a central opening 15 as shown clearly in Fig. 5 through which air may pass through the coils. A small cross member 16 is provided having an inwardly bent lower edge as shown in Fig. 1 extending nearly to the outer end of the deflector 12 forming a completion of the said deflector carrying the air upward through the channel 13 and outward through the aperture 17 in the upper part of the frame 14.

A thermostat is also employed indicated at 18 in Fig. 1 which may be of any approved type here shown as being provided with a coiled bimetallic element 19 which, through influence of change of temperature in the refrigerator, makes or breaks the circuit to the motor. This circuit is not here shown but the operation of a thermostat is so well known by those skilled in the art that further description or illustration of its connection with the circuit is deemed unnecessary. In the type of apparatus shown in Fig. 1 the thermostat 18 is preferably located in the upper end of the chamber in which the unit is introduced thus being subject to the

warmest air in the storage compartment. The thermostat of whatever type is fixed in relation to the unit and removable therewith.

To accommodate refrigerator boxes of various types which have ice chests and door openings therefor differing in size it is necessary to provide a unit that is very compact as is above described and further to provide an element in conjunction with the unit to take the place of the door of the ice compartment which must be removed to permit introduction of our improved apparatus. This problem has been solved by providing a frame 20 extending about the casing 11 of the unit near the forward open end. This frame may be permanently attached to the casing by means of lag screws 91 or other means. The peripheral edge of this frame 20 is shown in Fig. 1 as being beveled which is the usual form of peripheral edge of the door which is replaced by this frame. In manufacture, this frame is left rough at the periphery and is cut to fit the door opening. Thus, all that is necessary to install this apparatus in any ordinary box is to remove the ice compartment door, face off the frame 20 to correspond to the sides and shape of the door opening and insert the unit into the ice compartment. To secure the same in place, we provide plates 21 at several points above the periphery, and fastened to the frame 20 and the contiguous part of the refrigerator box. By this arrangement the unit is readily removable, permitting interchange of units when any particular unit becomes inoperative for any cause, enabling it to be taken out and repaired or, if the repair is one requiring considerable time, the corresponding unit may be substituted.

We have shown the coils 2 and 4 in cross section. It is to be understood that these coils are continuous in form, the coils 2 being connected with the compressor by the line 23 and with the expansion valve by the line 24, the coils 2 and 4 being provided with fins to increase the surface in contact with the atmosphere as is usual with this type of coil.

In the structure shown in Fig. 1, the entire unit is supported by the frame 20 but brackets could be additionally provided, if desired, particularly at the inner end of the unit, to sustain the weight thereof. It is also to be observed that this frame, shown at 20 in Fig. 1, is indicated at 30 in Figs. 2, 3 and 4 and may have a metal frame attached thereto indicated at 31 in the said figures. This frame 31 is preferably formed of angle iron attached to the member 30 and the unit may be simply inserted into this frame member 31 or removed therefrom without removal of the frame member 30, which fits the door opening. In the case of the apparatus shown in Fig. 1, coils 4 at the ends would rest in the frame member. The apparatus shown in Fig. 2 is essentially the same in general char-

acter, having the same type of compressor, motor and fan and high pressure coils, the only difference being that, at the rear and extending about the bottom and sides of the casing 40 providing the compartment 41, is a brine tank 42 which may rest in the frame 31. The thermostat in this Fig. 2 is shown at 44 being of a type having a tube 45 extending into the brine and containing an expandible fluid, as sulphur dioxide which, upon the expansion due to increased temperature of the brine, closes the circuit to the motor 46 and on contraction, due to decrease in temperature, breaks the circuit (which circuit is not here shown). As will be understood from Figs. 1 and 2, either type of artificial refrigerating apparatus may be utilized, our invention being confined more particularly to the unit as a whole, and its adaptability for replacement of the ice chamber door of an ordinary refrigerator, and extending into the storage compartment, and open to atmosphere, and insulated from the storage compartment of the refrigerator to prevent the temperature thereof being effected by the temperature of the atmosphere in the compartment 10 or 41 occupied by the apparatus. In Fig. 2 the expansion valve between the high and low pressure lines 47 and 43 is indicated at 48 within the apparatus chamber 41.

As heretofore stated, an object of the invention is to secure a compact arrangement of parts in the form of a unit that is attachable directly to the front walls of the refrigerator, replacing the door of the ice compartment, and these doors are usually about twenty inches high and fifteen inches wide and, by arranging this frame 20 or 30 intermediate the ends of the casing, housing the unit, we secure sufficient depth to accommodate the necessary apparatus. Thus, the high pressure coils extend outwardly from the face of the refrigerator to a greater or less extent, depending somewhat upon the character of the apparatus utilized and, if the brine tank is utilized as shown in Fig. 2, the forward end of the unit projects to a greater extent beyond the face of the refrigerator box, as a greater length over all of the unit is required to accommodate the brine tank. However, as heretofore stated, the character of refrigerating apparatus is not material to the invention as any well known character of apparatus adapted for the purpose may be utilized.

Our arrangement provides a large area of high pressure coils subject to the temperature of atmosphere and to a flow of air there-through by the means described, while the atmosphere of the refrigerator compartment is controlled by the temperature of the low pressure or expansion coils 4 or the brine in the tank 42. While the air drawn into the chamber 10 or 41 is heated somewhat above

atmospheric temperature, due to its passing through the high pressure coils, yet the constant flow of air tends to prevent overheating of the motor or compressor and the preferable compressor structure is of that type in which oil is carried in an enclosed casing to insure lubrication of the various parts.

From the foregoing description it is evident that an essential characteristic of our invention is in the provision of a casing carrying the refrigerating apparatus, and having heat insulated walls extending into the refrigerator compartment, preferably in the compartment heretofore ordinarily used for ice. In the usual refrigerator utilizing natural ice as a cooling element, a drip pan is provided indicated at 50 in the drawings which is provided with an outlet not here shown. This drip pan is a permanent structure supported by brackets in the interior of the refrigerator and the purpose is to catch the moisture condensed on the cooling coils 4 or brine tank 42 in the two types of artificial refrigerating devices here shown. This drip pan does not interfere with circulation of air to and from the cooling element of the device, the air flowing to and from the cooling element in the same manner as to and from the ice. Our improved structure therefore simply is of such compact form and arrangement as to be introduced in the ice compartment as a unit occupying the space heretofore provided for the ice and one principal feature of the invention is in the provision of the frame member and the casing with the heat insulated walls adapting the device to be introduced into the door opening of the ice compartment replacing the door and sealing the refrigerator compartment to atmosphere in equally as efficient manner as the door and in this respect it is to be noted that it is not material whether the casing housing the refrigerator parts has the member 20 fixedly secured thereto or whether the casing is moved into the frame member as indicated in Fig. 2. In the said last named figure the casing may be withdrawn leaving the frame 30 and 31 in place, the casing being a sliding fit in the frame member 30 and preventing a leakage of air between the frame 30 and casing 40 at the forward end. Either of the structures permit ready removal or introduction of the unit as a whole and the refrigerator box need not be reconstructed in any particular way to accommodate the unit.

Having thus fully described our invention, what we claim and desire to secure by Letters Patent of the United States is—

1. The combination with a refrigerator having an opening, of an artificial refrigerating unit including expansion and compression coils and apparatus for causing circulation of a refrigerant in the coils, and a heat insulating casing carrying the unit

- insertible through the opening and closing the opening when positioned therein, the said casing having an open end permitting circulation of air therein when the unit is in 5 operation.
2. The combination with a refrigerator having an opening, of an artificial refrigerating apparatus including a heat insulating casing housing and carrying the said apparatus, the said casing and apparatus being insertible as a unit into the opening of the refrigerator and closing said opening to atmosphere, and means for causing a circulation of air in the casing, the casing being 10 sealed to the refrigerator compartment.
3. The combination with a refrigerator having an opening leading to a compartment therein, of an artificial refrigerating unit insertible through the opening, said unit including a heat insulating casing open to atmosphere and housing a portion of the refrigerating apparatus and supporting the expansion coils of the system on the exterior, said apparatus including means for circulating 15 air within the casing and the casing closing the opening and sealing the refrigerator compartment to atmosphere when introduced thereinto.
4. The combination with a refrigerator having an opening leading to a compartment therein, of an artificial refrigerating unit insertible through the opening, said unit including a heat insulating casing open to atmosphere and housing the heat productive 20 portion of the refrigerating apparatus and supporting the expansion coils of the system on the exterior, said apparatus including means for circulating air within the casing and the casing closing the opening and sealing the refrigerator compartment to atmosphere when introduced thereinto.
5. The combination with a refrigerator having an opening leading to a compartment therein, of an artificial refrigerating unit comprising a heat insulating casing having an opening to atmosphere and being insertible into the compartment through the refrigerator opening, means in conjunction 25 with the unit for sealing the said opening, and artificial refrigerating apparatus, the heat productive portion of which is housed within the casing and including means for circulating air therethrough, and the expansion coils of which are located on the exterior 30 of the casing within the compartment.
6. The combination with a refrigerator having a compartment and an opening on one side to atmosphere, of an artificial refrigerating unit including an open ended, 35 heat insulated, casing provided with a frame near the open end fitting the refrigerator opening and sealing the compartment thereof to atmosphere, the said casing within the compartment being spaced from the walls 40 thereof and the cooling coils of the unit being 45 mounted on the exterior of the casing within the refrigerator compartment.
7. The combination with a refrigerator having an opening leading to a compartment therein, of an artificial refrigerating unit including expansion and compression coils and power apparatus for circulating the refrigerant in the coils, and a heat insulated casing carrying and housing the unit, said casing being insertible into the refrigerating 50 compartment closing the said opening therein, the casing having an open end practically occupying the position of the opening of the refrigerator compartment and the cooling coils of the unit being mounted on the exterior of the casing within the compartment.
8. The combination with a refrigerator having an opening leading to a compartment to and from which air in the refrigerator may flow, of an artificial refrigerating unit including expansion and compression coils, power apparatus for circulation of the refrigerant therein, an open ended, heat insulated, casing housing the said unit and insertible into the opening of the compartment with the opening of the casing registering practically with the opening of the refrigerator compartment, means in conjunction with the unit for closing the compartment 55 to atmosphere upon introduction of the casing thereinto, the said casing being mounted in the compartment in spaced relation with the walls thereof and the cooling coil of the refrigerating apparatus being supported 60 within the compartment on the exterior of the said casing.
9. The combination with a refrigerator having an opening leading to a compartment therein, of an artificial refrigerating unit including a casing having heat-insulated walls housing the apparatus and insertible into the compartment through the opening and closing the compartment to external atmosphere, the casing having an opening to atmosphere 65 for discharge of heat from the interior thereof and the cooling element of the unit being exposed to the atmosphere of the refrigerator compartment.
10. The combination with a refrigerator having an opening, of an artificial refrigerating unit insertible through the opening, the said unit including a heat insulated casing for the operating parts, means for circulating air in the casing to discharge the heat units 70 developed by the apparatus, a cooling element exteriorly of the casing on the end projecting into the refrigerator, and a frame about the forward end of the casing fitting the opening and detachably secured therein.
11. The combination with a refrigerator having an opening, of an artificial refrigerating unit including a casing for the operating parts, means for circulating air in the casing 75 to discharge the heat units developed by the 80

- apparatus, said casing being insertible into the refrigerator through the opening, the walls of the casing projecting into the refrigerator being heat insulated, a frame 6 about the forward end of the casing fitting the refrigerator opening the cooling element of the unit being on the exterior of the heat insulated walls in contact with the atmosphere of the refrigerator compartment. 10 12. The combination with a refrigerator having an opening, of an artificial refrigerating unit comprising a motor, a compressor, high and low pressure lines, a casing having heat insulated walls open at one end, the high 15 pressure coils extending across said open end, the low pressure coils being on the exterior of the casing at the opposite end, the unit being adapted to be inserted into or withdrawn from the refrigerator through the opening. 20 13. The combination with a refrigerator having an opening, of an artificial refrigerating unit including a casing, housing the operating parts and a circulating system for a refrigerant with the cooling element on the 25 exterior of the casing at one end, a frame at the forward end of the casing adapted to fit in the opening upon introduction of the unit into the refrigerator, said forward end of the casing being open to atmosphere, the high 30 pressure coils of the circulating system being located across the said opening, and means for causing movement of air through the coils into the casing and thence outwardly thereof at the forward end. 35 14. The combination with a refrigerator having a front opening, of an artificial refrigerating unit comprising a casing forming a chamber housing the mechanism, said chamber being open at the front end to atmosphere 40 and adapted to be inserted into the opening to close the same with the major portion of the casing extending into the refrigerator, said portion of the casing having heat insulated walls, said unit including high pressure lines 45 extending across the open end of the casing and low pressure lines positioned about the exterior of the casing within the refrigerator, a deflector member dividing the interior of the casing at the forward end, a fan below 50 the deflector for drawing air through the high pressure lines into the chamber of the casing, the deflector providing for a discharge of the said air through the front opening at the upper side. 55 15. The combination with a refrigerator having an opening, of an artificial refrigerating unit comprising a casing having heat insulated walls and open to atmosphere at the forward end, said casing being adapted for 60 introduction into the refrigerator through the opening and suspended in position to close the said opening, the said unit comprising a compressor and motor within the casing, a high pressure line extending across the 65 open end of the casing, means for drawing air into and discharging from the interior of the casing at the forward end, low pressure lines positioned exteriorly of the insulated walls of the casing within the refrigerator, a thermostat subject to influence of the temperature of 70 the atmosphere of the refrigerator and adapted to control operation of the motor. 16. An artificial refrigerating unit comprising a casing having heat insulated walls, a motor and compressor within the casing, the forward end of which is open to atmosphere, a circulating system having a high pressure line positioned at the said forward end, and a low pressure line positioned exteriorly of the casing about the sides and opposite end of the casing, and means for causing a flow of air into and out of the casing through the forward end. 75 17. An artificial refrigerating unit comprising a casing having heat insulated walls, the forward end thereof being open, said apparatus being housed within the chamber provided by the casing and including high pressure coils positioned across the open end of the casing and connected with the compressor, an expansion valve to which the high pressure lines are connected, low pressure coils positioned about the exterior of the heat insulated walls connected with the expansion valve and a return line connected with the compressor, a fan for blowing air through the high pressure coils into the casing, the casing having a channel by means of which air forced through the coils is discharged through the said open end of the casing, the said unit being adapted to be introduced into a refrigerator compartment with the low pressure coils exposed to the atmosphere of the compartment. 80 18. An artificial refrigerating unit comprising a casing having heat insulated walls about five of the sides thereof, the remaining side being open, a compressor and motor within the casing, a circulating system for the refrigerant comprising a discharge line from the compressor, a series of coils connected with said discharge line providing the high pressure side of the circulating system, an expansion valve to which the high 85 pressure coils are connected, a low pressure line including a series of coils about the exterior of the heat insulated walls connected at one end with the expansion valve and having a line extending into the chamber of the casing and connected with the intake of the compressor, a fan in the casing for drawing air into the casing through the high pressure coils, a deflector dividing the forward part of the casing into two channels whereby air drawn through the coils in one 90 channel is discharged through the other channel, the said unit being adapted to be suspended in a refrigerator compartment with the open end thereof open to atmosphere externally of the compartment, a temperature 95 100 105 110 115 120 125 130

- controlled device subject to the influence of change of temperature in the compartment in which the unit is positioned adapted to control the operation of the motor.
19. In refrigerating apparatus, a refrigerator having a compartment, a casing formed of heat insulated walls extending into the refrigerator compartment from one of the walls thereof and having an opening through the said wall, an artificial refrigerating apparatus including a compressor for circulating refrigerant, the compressor being located in the casing and removable through said opening, an expansion coil located on the exterior of the casing and exposed to the atmosphere of the refrigerator compartment, a condensing coil, and means for operating the compressor.
20. The combination with a refrigerator having an opening to a refrigerated compartment thereof, of a reentrant casing at the said opening, an artificial refrigerating apparatus, the heat productive elements of which are within the casing and shielded thereby from the atmosphere of the refrigerated compartment, and the cold productive elements of which are within the refrigerated compartment, means for closing the refrigerator opening, and means providing for a circulation of air within the casing.
21. The combination with a refrigerator having an opening in the wall thereof to a refrigerated compartment therewithin, of a reentrant casing insertible in the said opening and formed with heat insulating walls coextensive with the refrigerator walls and having an open end, an artificial refrigerating apparatus, the heat productive elements of which are housed within the casing, the said open end being of a size to permit introduction or removal of the said elements therethrough and the cold productive elements of which are exteriorly of the casing within the refrigerator compartment, and means for discharging the heat evolved through operation of the apparatus from the casing.
22. The combination with a refrigerator having a compartment, of a reentrant casing therewithin formed with heat insulated walls, an artificial refrigerating apparatus including a motor and a compressor and a circulating system for refrigerant including a condenser and expansion coils, the said compressor being mounted within the casing and shielded thereby from the refrigerator compartment, the said expansion coils being exteriorly of the casing within the refrigerator compartment and the said condenser being exteriorly of the refrigerating compartment and shielded therefrom by the said casing, the said casing having an opening permitting introduction or removal of the motor and compressor in assembly or disassembly of the unit, and means for circulating external atmosphere about the compressor and motor and through the condensing coils to discharge the heat evolved through operation of the apparatus away from the refrigerator.
23. The combination with a refrigerator, of a reentrant chamber forming a component part of the refrigerator walls and formed of heat insulated walls spaced from the walls of the refrigerator interiorly thereof, an artificial refrigerating apparatus, the heat productive and radiating elements of which are shielded from the compartment by the walls of the said reentrant chamber and the cold producing element of which is on the exterior of the said chamber walls and within the said space between the walls of the chamber and of the refrigerator, and means for cooling the said heat productive and heat radiating elements.
24. In artificial refrigerating apparatus, the combination with a refrigerator formed of heat insulated walls and having an opening through the wall thereof, of a casing formed of heat insulated walls insertible through the said opening and having an open end substantially coinciding with the opening of the refrigerator, means for supporting the said casing in position, means in conjunction with the casing for sealing the refrigerator opening, and an artificial refrigerating apparatus, the heat productive elements of which are housed within the casing and shielded thereby from the atmosphere of the refrigerator compartment and the cold productive element of which is exteriorly of the casing and within the refrigerator compartment.
25. The combination with a refrigerator having a reentrant portion formed of heat insulating walls extending into the refrigerated space thereof, of an artificial refrigerating apparatus including a motor and compressor and a circulating system, the expansion side of which is within the refrigerator exteriorly of the reentrant portion of the said casing, the opening of said reentrant portion being of a size to permit introduction of the compressor thereinto and the walls of which prevent the said compressor from materially influencing the temperature of the refrigerator compartment.
26. A refrigerator having a reentrant chamber formed of heat insulating walls coextensive with one of the walls of the refrigerator and in spaced relation with the remaining walls thereof, and an artificial refrigerating unit, comprising a motor and compressor and a circulating system including a condenser and expansion coils, the expansion coils being within the refrigerator compartment exteriorly of the said chamber walls, said walls shielding the refrigerator compartment from influence of heat evolved by the apparatus.
27. The combination with a refrigerator

having a chamber formed with heat insulated walls coextensive with the refrigerator walls and opening to atmosphere, of an artificial refrigerating apparatus, the heat
 5 productive elements of which are housed within the chamber, the said opening of the chamber being of a size to permit introduction or removal of the said elements therethrough, and the cold productive elements of
 10 which are supported on the exterior of the chamber within the refrigerator, and means for cooling the heat productive elements of the apparatus.

28. In artificial refrigerating apparatus, a
 15 cabinet having a space to be refrigerated and provided with a re-entrant chamber extending into the said space with all of its walls in spaced relation with the cabinet walls, the wall of the cabinet having an opening lead-
 20 ing to the interior of the re-entrant chamber, said chamber providing a housing for the operating parts of the refrigerating apparatus including a heat dissipating element, and a heat absorbing element supported on
 25 the exterior of the re-entrant chamber and adapted for connection or disconnection with the complemental parts of a refrigerating apparatus.

29. In artificial refrigerating apparatus, a
 30 cabinet having heat insulated walls, a chamber formed of heat insulated walls in fixed relation with a wall of the cabinet and extending into the interior of the cabinet, said cabinet wall having an opening leading to
 35 the interior of the chamber, a frame for covering the opening of the cabinet wall and having a pair of spaced openings, artificial refrigerating apparatus housed within the chamber, and a fan in the chamber through
 40 rotation of which air is drawn from the exterior of the cabinet through one of the openings and about the apparatus therein and discharged through the other of the openings.

In testimony whereof, we sign this speci-
 45 fication.

CLARENCE M. HOLLEY.
 HOWARD L. FOSTER.
